UNITED STATES PATENT OFFICE.

WILLIAM H. D. FORD, OF NEW YORK, N. Y., ASSIGNOR TO WESTERN ELECTRIC COMPANY, INCORPORATED, OF NEW YORK, N. Y., A CORPORATION OF NEW YORK.

ELECTROMAGNETIC DEVICE.

Application filed December 27, 1919. Serial No. 247,807.

To all whom it may concern:

Be it known that I, WILLIAM H. D. FORD, a citizen of the United States, residing at New York, in the county of New York, State of New York, have invented certain new and useful Improvements in Electromagnetic Devices, of which the following is a full, clear, concise, and exact description.

This invention relates in general to electromagnetic devices and more particularly to an electromagnetic device which is prevented from being operated accidentally by means of an electrically operated latch.

Under various service conditions, it is often required to have an electromagnetic device, such as a relay, so arranged that when operated it will remain locked in the operating position until released by other means. The device may be held in the operated position electrically, by means of a locking winding, or mechanically, by means of a latch, as disclosed for example in my copending application, Serial No. 268,524, filed December 27, 1918. With such a device, however, there is the disadvantage that if it is operated momentarily by accident, as by jarring, it remains locked up in the operated position. This feature is of particular importance in connection with relays or other electromagnetic devices which are mounted in close proximity to heavy guns, since the concussion is often sufficient to cause the vibration of the relay armature an amount sufficient to cause the device to be locked up in its operated position. Also, in various other places, a relay may be subjected to more or less jarring which would cause the momentary closure of the contacts springs.

It is therefore the object of the present invention to provide an electromagnetic device in which the armature is normally held in a locked position until released electrically.

To attain this object and in accordance with a feature of this invention, there is provided a second armature or magnetic latch which prevents the circuit controlling armature from moving until the device is operated electrically. This and other features of the invention will be more clearly understood from the following description of the invention and the accompanying drawing, in which there is shown a view in

perspective of a device embodying this invention. 55

Referring now to the drawing, there is disclosed an electromagnetic device which includes a relay 5 of a familiar type provided with a core extension or pole piece 6 and a U-shaped armature 7, the free end of which is so formed as to have a flat portion 8 of a shape corresponding to that of the pole piece 6. The outer legs of armature 7 are provided with studs 9—9 of hard rubber or similar insulating material. These studs bear against the free ends of contact springs 10—10 which are adapted to move into contact with the springs 11—11 upon the movement of armature 7 toward the pole piece 6. Rigidly secured to the pole piece 6 is a threaded stud 12 which extends through a suitable slot in the armature portion 8 and is provided with a nut 3 having a shouldered portion which is adapted to bear 75 against the outer side of the armature when the latter is in its normal position, thus acting as a back stop and limiting the movement of the armature resulting from the tension of the springs 10—10. 80

A similar type of relay 14 having a pole piece 15 and an armature 16 is mounted adjacent to relay 5 and in a fixed position relative thereto. This is accomplished by means of a plate 17 and a spacer rod 18 both of which are of brass or other similar non-magnetic material and are rigidly secured to the pole pieces of the respective relays. Pivotaly mounted upon the right-hand side of plate 17 by means of a trunnion screw 19 is a locking lever 20, of brass or similar non-magnetic material, the upper end of which is bevelled as shown at 21, while the lower end is provided with a recess or latch portion 22. The armature of relay 5 is provided with a pin 23 adapted to engage the latch 22 when the armature of relay 5 is in its operated position and the armature of relay 14 is provided with a pin 24 which is adapted to bear against the bevelled portion 21. A second latching lever 26 is pivotally mounted on the left-hand side of plate 17 by means of a trunnion screw 27. This lever is of magnetic material, preferably soft iron, and lies in close proximity to the pole piece 6. It is provided with a shouldered extension 28 extending directly above a pin 29 fastened to the 95 100 105

armature 7. A helical spring 30 is secured under tension between the levers 20 and 26 in the manner shown, thereby tending to cause the respective levers to bear against the pins 23 and 29.

In the normal position of this device, as illustrated, movement of the armature is prevented by means of the shoulder portion 28 bearing against the pin 29 until relay 5 is operated electrically. Upon current flowing the winding of relay 5, lever 26 is first attracted to the right, tending to bridge the gap between the pole pieces 6 and the armature extension 8. As this movement takes place, the shoulder portion 28 moves away from pin 29, allowing the armature portion 8 to approach the pole piece 6, thus permitting the springs 10-10 to engage the springs 11-11. In its operated position, the pin 23 comes into alignment with the latch portion 22 of lever 20 and the latter is drawn into the locked position by means of the tension of spring 30. The device thus remains in a locked operated position until a circuit is closed through the relay 14, in which case, the pin 24 in armature 16 bears against the bevelled portion 21, causing movement of the upper portion of lever 20 to the left and the disengagement of the locking portion 22 with the pin 23. Relay 14 is provided with a spring member 31 which bears against an insulating stud 32 in the armature 16 and causes the latter to be returned to its normal position when the flow of current ceases.

What is claimed is:

1. A circuit controlling device comprising circuit controlling springs; an electromagnet; a pair of directly interlocking armatures for said electromagnet, one of said

armatures being a circuit controlling armature arranged to actuate said circuit controlling springs; a catch; means for causing said catch to engage said circuit controlling armature to hold it in the operated position; and a second electromagnet for disengaging said catch from said circuit controlling armature.

2. A circuit controlling device comprising circuit controlling springs; an electromagnet; a pair of directly interlocking armatures for said electromagnet, one of said armatures being a circuit controlling armature arranged to actuate said circuit controlling springs; a catch; a means for causing said catch to engage said circuit controlling armature to hold it in the operated position; a second electromagnet and an independent armature for said second electromagnet arranged to disengage said catch from said circuit controlling armature.

3. A circuit controlling device comprising circuit controlling springs; an electromagnet; a pair of directly interlocking armatures for said electromagnet, one of said armatures being a circuit controlling armature arranged to actuate said circuit controlling springs; a catch; means for causing said catch to engage said circuit controlling armature to hold it in the operated position; a second independent electromagnet; an armature for said second electromagnet arranged to disengage said catch from said circuit controlling armature; and spring means tending to maintain all of said armatures in a non-operated position.

In witness whereof, I hereunto subscribe my name this 23rd day of December A. D., 1919.

WILLIAM H. D. FORD.
